MIRROR FOR A MOTOR VEHICLE

David Warwick Neale, Waterfall Lane, Old Hill,
Staffordshire, England

Filed Aug. 18, 1965, Ser. No. 86,630

Term of patent 14 years

(Cl. D14—6)

FIG. 1 is a rear perspective view of the mirror embodying my new design;

FIG. 2 is a front view of the mirror of FIG. 1;

FIG. 3 is a rear elevational view of the mirror of FIG. 1;

FIG. 4 is a bottom view of the mirror of FIG. 1, on a reduced scale; and

FIG. 5 is a side elevational view of the mirror of FIG. 1.

The side not shown is a mirror image of the side shown in FIG. 5.

I claim:

The ornamental design for a mirror for a motor vehicle, as shown and described.
